UNITED STATES PATENT OFFICE.

EBENEZER R. GAY, OF DUBUQUE, IOWA.

RELISHING-MACHINE.

SPECIFICATION forming part of Letters Patent No. 223,500, dated January 13, 1880.

Application filed May 3, 1879.

To all whom it may concern:

Be it known that I, EBENEZER R. GAY, of Dubuque, in the county of Dubuque and State of Iowa, have invented a new and Improved 5 Relishing-Machine, of which the following is a specification.

My invention relates to a relishing or tenon-finishing machine for use on rails for doors, blinds, panels, or other wood-work having 10 rails with tenons and a groove or rabbet for panels. In such work, when the groove is not as wide as the tenon is thick, or does not have the same face as the tenon, a rib or projection is left, which has to be removed, and my improved machine is adapted for such operation. 15

I make use of a reciprocating bit and a knife fitted to act simultaneously and in directions at right angles to each other upon the rail that is placed on a bed and held by an adjustable 20 gage and clamps; and the machine is fitted for operation by foot or other power.

In the accompanying drawings, Figure 1 is a plan view of the improved machine. Fig. 2 is a vertical transverse section on line x x of 25 Fig. 1.

Similar letters of reference indicate corresponding parts.

A is the frame of the machine, on which is fixed the bed or table B. Beneath the bed B, 30 in suitable slideways a , is fitted a vertical slide or head, b , that carries the cutter c . This cutter c is adjustable on slide b , to compensate for wear, and works through a slot in bed B. Upon bed B is an adjustable box, d , formed 35 with an aperture for receiving and supporting the horizontally-sliding bit e . The shape of the cutting-point of e is adapted for the particular work to be done, and the bit may be changed as required. The cutters are simultaneously operated by a main lever, f , that is connected by a crank with a shaft, g , that is driven by suitable power, or, when the machine is operated by foot, lever f will be connected to a foot-lever. (Represented by dotted 40 lines at h .)

Lever f connects, by a short lever, i , with slide b , and by a bent lever, k , with the shank of bit e , levers i k being slotted at their junction with the parts b e f , whereby cutter c is raised 45 and bit e moved inward toward cutter c at the

same moment. A spring, l , is fitted to withdraw the cutters when the machine is operated by foot.

Upon bed B is a gage, m , attached adjustably by the lugs n . This gage sustains the 55 rail against the action of bit e , and its position regulates the depth to which c cuts. A fixed clamp, o , also on bed B, holds the end of the rail down upon the bed against cutter c . A gage, p , adjustable on bed B lengthwise of the 60 rail, abuts against the shoulder of the tenon to regulate the position of the cut made by bit e .

In Fig. 3 is represented a rail, q , formed with a square-shouldered tenon, r , and groove 65 s . The groove s being narrower than the tenon, the projecting edges t from the shoulder to the end of the tenon have to be removed. This is the simplest form of rail, and in this case the bit e would have a straight cutting-edge, and cut across on line with the shoulders to the depth of the groove. If the shoulder be in the form of an ogee the bit will correspond in shape, and in some cases the rails are rabbeted instead of grooved, and formed 70 with an ogee shoulder.

The machine is adapted for any work of this character, and the relishing is done with rapidity and much more economically than it can be done by hand.

The machine is simple and durable, and requires but a small amount of power to operate it.

Having thus described my invention, I claim as new and desire to secure by Letters 85 Patent—

1. The combination, with the bed B, slide b , having vertical cutter c , and bit e in block d , of the slotted elbow-lever k and the slotted lever i , pivoted near its middle to a pendant of 90 frame, said levers being each connected at one end with the actuating-lever f , as shown and described.

2. The combination, with cutter c and bit e , of the adjustable gages k p and fixed clamp o , 95 as and for the purposes specified.

EBENEZER R. GAY.
